(57) **CLAIM**

The ornamental design for a vehicle, toy, and/or other replicas, as shown and described.

DESCRIPTION

This application is related to the following co-pending applications: Application Ser. No. 29/294,032, entitled “Rear Fender for a Vehicle”; Application Ser. No. 29/294,056, entitled “Trunk Lid for a Vehicle”; Application Ser. No. 29/294,055, entitled “Front Fender for a Vehicle”; Application Ser. No. 29/294,031, entitled “Door for a Vehicle”; Application Ser. No. 29/294,015, entitled “Door for a Vehicle”; Application Ser. No. 29/294,014, entitled “Rear Bumper for a Vehicle”; and Application Ser. No. 29/294,060, entitled “Front Bumper for a Vehicle”.

FIG. 1 is a left, front perspective view of a vehicle, toy, and/or other replicas according to my novel design, the right, front perspective view being mirror symmetrical;

FIG. 2 is a left, rear perspective view thereof, the right, rear perspective view being mirror symmetrical;

FIG. 3 is a left side view thereof;

FIG. 4 is a right side view thereof;

FIG. 5 is a front view thereof;

FIG. 6 is a rear view thereof; and,

FIG. 7 is a top view thereof.

The broken lines are for illustrative purposes only and form no part of the claimed design.
